UNITED STATES PATENT OFFICE.

WILLIAM E. FOULKES, OF CHICAGO, ILLINOIS.

BOAT CONNECTION.

Application filed April 4, 1924. Serial No. 704,172.

To all whom it may concern:

Be it known that I, WILLIAM E. FOULKES, a citizen of the United States, and a resident of the city of Chicago, county of Cook, 5 and State of Illinois, have invented certain new and useful Improvements in Boat Connections, of which the following is a specification.

My invention relates to improvements in 10 boat connections and has for its object the provision of an improved connection by means of which two boat members may be secured together for movement of one by the other which will permit of necessary 15 movements between said boat members to permit of use in comparatively heavy seas.

Other objects will appear hereinafter.

The invention consists in the combinations 20 and arrangements of parts hereinafter described and claimed.

The invention will be best understood by reference to the accompanying drawings forming a part of this specification, and in which,

Fig. 1 is a top plan view of two boat members connected by means embodying the invention;

Fig. 2 a side view of the same;

Fig. 3 an enlarged rear elevation of an 30 abutment member employed in the connection;

Fig. 4 a section taken on line 4—4 of Fig. 3; and

Fig. 5 a section taken on line 5—5 of 35 Fig. 3.

The preferred form of construction as 40 illustrated in the drawings comprises a supporting member consisting of a central block 6 having side blocks 7 hinged thereto to swing on vertical axes as shown. The central block 6 is provided on one side with a vertical slot or notch 8 adapted and arranged to fit over the end of a pointed boat member as indicated by the dotted lines at 45 the left of Fig. 1. The side blocks 7 are provided with securing eyes 9 for engagement by suitable cables or lines 10 and whereby the supporting member may be securely bound to the stern of a barge or the 50 like 11. Where the stern of the barge is square and flat as indicated at the center of Fig. 1 the supporting member will be secured thereto in flat condition as shown. Where the stern of the barge is pointed as 55 indicated at the left of Fig. 1 the slot 8 will be fitted over the prow 12 of the barge

and the supporting member bound in place as indicated by the dotted lines.

The central block 6 is provided with a rearwardly extending abutment post 13 60 which is pivotally mounted in a suitable socket 14 and held in place by a threaded cap 15 whereby the abutment member 13 is permitted to rotate freely on a horizontal longitudinal axis. Abutment member 13 is 65 provided with a vertical slot or notch 16 having a vertically convex bottom 17, said notch being arranged to fit over the prow of a tug or the like 19 and the convex bottom 17 of the slot 16 permitting of vertical rocking 70 between the barge and tug in heavy seas. The swiveled mounting of the abutment member 13 permits of relatively lateral rocking or rolling between the barge and tug 75 in heavy seas.

The barge and tug are bound together by means of lines or cables 20 engaging windlasses or capstans 21 of the side rails of the bow of the tug 19 as shown. Suitable spring members 22 are included in the 80 cables 20 and thus afford yielding connection between the boat and barge which permits of the necessary movements between the two in heavy seas. Obviously by adjusting the capstans 21 the relative arrangement between the barge and tug may be varied to assist in steering. 85

By this arrangement the barge and tug may be securely fastened together for propulsion of the barge and the connections are 90 such as to permit of necessary relative movements between the barge and tug in heavy seas.

While I have illustrated and described the preferred form of construction for carrying 95 my invention into effect, this is capable of variation and modification without departing from the spirit of the invention. I, therefore, do not wish to be limited to the precise details of construction set forth, but 100 desire to avail myself of such variations and modifications as come within the scope of the appended claims.

Having described my invention, what I claim as new and desire to secure by Letters 105 Patent is:

1. The combination of two boat members arranged in towing relation; a member swivelled to one boat and constituting an abutment between the boat members, said 110 swivelled member having a slot receiving the prow of the other boat member; and

means connecting said boat members allowing relative pitching movements thereof, substantially as described.

2. The combination of two boat members arranged in towing relation; a block hinged to the end of one boat member; an abutment member swivelled to said block and having a slot receiving therein the prow of the other boat member; and means connecting said boat members allowing relative pitching movements thereof, substantially as described.

3. A boat connection comprising a supporting member adapted to be secured to the end of a boat; and an abutment member pivotally mounted on said supporting member to rotate on a longitudinal axis, said abutment being provided with a slot for the reception of the prow of a boat member, substantially as described.

4. A boat connection comprising a supporting member adapted and arranged to be secured to the end of a boat member; and an abutment member pivotally mounted on said supporting member to rotate on a longitudinal axis, said abutment member being provided with a slot for the reception of the prow of a boat member, the bottom of said slot being vertically convex in form, substantially as described.

5. A boat connection comprising a supporting member adapted and arranged to be secured to the end of a boat member; an abutment member pivotally mounted on said supporting member to rotate on a longitudinal axis, said abutment member being provided with a slot for the reception of the prow of a boat member, the bottom of said slot being vertically convex in form; and cable members having yieldable spring connections therein for securing said boat members together, substantially as described.

6. A boat connection comprising a supporting member consisting of a central block and two side blocks hinged thereto to swing on vertical axes, said central block being provided with a vertical groove in one side; an abutment member swivelled to the other side of central block to rotate on a horizontal axis, said abutment member being provided with a vertical slot having a vertically convex bottom; and attaching members on said hinged blocks for securing said supporting member in place at the end of a boat member, substantially as described.

In testimony whereof I have signed my name to this specification.

WILLIAM E. FOULKES.
